[57] **CLAIM**

The ornamental design for a sign holder with sloped top, as shown and described.

DESCRIPTION

FIG. 1 is a perspective view of the front;

FIG. 2 is a perspective view of the back;

FIG. 3 is a front elevation;

FIG. 4 is a back elevation;

FIG. 5 is a side elevation;

FIG. 6 is a top plan view;

FIG. 7 is a bottom plan view; and,

FIG. 8 is an alternate front elevation, showing an alternate design of the lower corners.

The second embodiment differs only in the two lower, squared corners.
